UNITED STATES PATENT OFFICE.

RONALD A. SMITH, OF MOUNT PLEASANT, PENNSYLVANIA.

COMBINED LETTER-SHEET AND ENVELOP.

1,318,236.

Specification of Letters Patent.

Patented Oct. 7, 1919.

Application filed March 9, 1917. Serial No. 153,623.

To all whom it may concern:

Be it known that I, RONALD A. SMITH, a citizen of the United States, residing at Mount Pleasant, in the county of Westmoreland and State of Pennsylvania, have invented certain new and useful Improvements in Combined Letter-Sheets and Envelops; and I do hereby declare the following to be a full, clear, and exact description 5 of the invention, such as will enable others skilled in the art to which it appertains to make and use the same.

This invention relates to improvements in combined letter sheets and envelops.

15 The object of the invention is the provision of a rectangular sheet, which when folded provides a combined letter sheet and envelop, and one that may be easily and quickly folded and the sheet located on the 20 interior and completely concealed when folded to present the envelop.

Another object of this invention is the provision of a rectangular sheet, which when folded completes a combined letter sheet 25 and envelop and is of such a character, as to be simple, practical and comparatively inexpensive in construction, and one that can be manufactured and sold at a small cost.

30 With these and other objects in view, the invention consists of the novel combination and arrangement of parts hereinafter more fully described and claimed.

In the drawings:

35 Figure 1 is a plan view of a rectangular sheet of paper from which my improved envelop and letter sheet may be formed.

Fig. 2 is a plan view showing the sheet folded transversely intermediate its ends 40 and is the first step in the folding of the rectangular sheet.

Fig. 3 illustrates the third step of the folding of the sheet and is folded on a diagonal line to represent a triangle,

45 Fig. 4 illustrates the fourth step showing the ends of the triangle bent inwardly overlapping one another, and one flap located beneath the wing,

Fig. 5 illustrates the envelop in complete 50 folded position.

Fig. 6 is a front view of the envelop in the folded position,

Fig. 7 is a sectional view taken on the line 7-7 of Fig. 5,

55 Fig. 8 is a sectional view taken on the line 8-8 of Fig. 4.

Referring in detail to the drawings, the numeral 1 illustrates a rectangular sheet of paper which constitutes a letter sheet and envelop when in folded position, which will 60 be hereinafter more fully described.

The sheet is first folded on the transverse line 2, which line is adjacent one end of the sheet constituting approximately one-third of the sheet. The sheet is then folded 65 on the diagonal line 3 forming the triangle 4, as shown in Fig. 3. Fig. 2 illustrates the first step of the operating showing one end of the sheet 1 folded on the line 2 and having one end cut away as at 5, the purpose 70 of which will be hereinafter more fully described.

It will be understood that by folding the rectangular sheet on the line 2, and on the diagonal line 3, it provides a double sheet, 75 the upper flap of the double sheet being bent back upon itself on the line 6 and the end flaps 7 of the triangle are bent on the lines 8 and overlap one another and overlap the top sheet 9 when folded on the line 6, thus leaving a sealing flap 10, which has 80 suitable adhesive material 11 thereon. The sealing flap 10 is substantially triangular and is adapted to be folded down and completely cover the ends 13 and end of the 85 members 7 and is sealed to complete the envelop. The rectangular sheet 1 is folded on the line 2 as described and this portion provides the lower end of the inner writing sheet 14 and when the sheet 14 is folded on the diagonal line 3 the writing surface is 90 completely hidden on the interior, and provides a substantially triangular shaped member, the ends of which designated 7 are folded on the lines 8 and overlie the upper 95 portion of the upper fold constituted by the folding on the line 3, the flap 10 is then sealed completing a plane surface 15 for the address or the like.

It being understood that the line 16 of 100 the envelop or sealing flap 10 can be perforated to permit the same to be readily slit so that the same can be unfolded and the writing matter on the interior of the sheet exposed to view, the outer portion not 105 containing writing matter will be the inner face of the sealing flap 10.

What is claimed:

As an article of manufacture, a letter sheet and envelop formed from a rectangular oblong sheet having an inwardly extending 110 triangular shaped notch formed in one

longitudinal edge thereof adjacent its lower end, said sheet being folded on a transverse line extending from the apex of the triangular shaped notch to the opposite side of the sheet to form a square blank and then doubled on a diagonal line extending from one corner to the opposite diagonal corner to form a pair of superimposed triangles of which the acute base angles are folded inwardly on a diagonal line to overlap at their apexes and to overlie the body of the envelop, leaving the right angle portion to form a covering flap to overlap and seal the base angles, said right angle portions being

arranged to extend below the base angles to 15 engage the body of the envelop, the apex of the outer superimposed triangle forming the right angle attaching portion overlying the notch portion of the sheet so as to engage the body of the envelop below the base angles, as and for the purpose specified. 20

In testimony whereof I affix my signature in presence of two witnesses.

RONALD A. SMITH.
